UNITED STATES PATENT OFFICE.

WILLIAM J. CRAWFORD AND EDWARD R. INMAN, OF FRANKLIN, PENNSYLVANIA.

COMPOSITE TIE FOR RAILWAYS.

1,087,281.

Specification of Letters Patent. Patented Feb. 17, 1914.

Application filed February 12, 1912. Serial No. 677,057.

To all whom it may concern:

Be it known that we, WILLIAM J. CRAWFORD and EDWARD R. INMAN, citizens of the United States, residing at Franklin, in the county of Venango and State of Pennsylvania, have invented certain new and useful Improvements in Composite Ties for Railways, of which the following is a specification.

- 10 The object, construction and application of our improved tie are herein set forth with sufficient clearness to enable those skilled in the art to which it appertains, to make and use the same.
- 15 It is a fact well known to railway engineers, that there is no material of which a tie can be made, that is generally more satisfactory than wood, but upon account of the growing scarcity of suitable timber from 20 which to make ties, some suitable construction is being sought for, which may be made to take the place of wood. There are many serious objections to metal ties, and among these, is the fact that their use necessitates a variety of special accessories, such as spikes, or their equivalents, rail joints, etc.
- 25 It is the object of our invention to provide a composite tie, composed of both wood and metal, which will not require any modification of the rail, its joints or the spikes, in laying or repairing track, and which will readily interchange with a wooden tie of the usual construction, without necessitating any special provision therefor. This object 30 is attained by constructing the body of the tie of metal, and providing suitable mortises or housings therein, for the reception of wooden blocks for the rails to rest upon, and which, with the exception of length, 35 have otherwise substantially the same dimensions as the standard railway tie.

One form of construction wherein our invention is practically embodied, is illustrated in the drawings, the various figures 40 of which are as follows:

Figure 1 is a plan view of one end of a tie, embodying our invention, with a wooden block in position; Fig. 2 is a side elevation of Fig. 1; Fig. 3 is a side elevation, with 45 the mortise shown in section upon the line III III of Fig. 1, the block being removed; Fig. 4 is a plan view of one end of the metallic portion of our tie, from which the block is removed; Fig. 5 is a transverse section upon line V V of Fig. 4; Fig. 6 is a 50 plan view of one end of our tie, showing a

tie plate in its proper position upon the wooden block; Fig. 7 is a section upon line VII VII of Fig. 6, and in addition thereto, a rail is shown in position upon the tie; 60 Fig. 8 is a plan view of an improved tie plate, which we prefer to use with our tie.

The same reference characters are applied to identical parts in all the views.

The construction here shown, is substantially as follows:—We construct a cross tie or body 1, which is preferably about nine feet in length, though it may be more or less, as desired, and at a suitable distance apart therein,—depending upon the gage 70 of the road upon which the tie is to be used,—we form boxes or mortises 2, (one end only being shown), for the reception of a wooden block 3, which is preferably about the width and thickness of a standard 75 wooden tie. Mortise 2 is somewhat longer and wider than the block 3, but its depth is such that the block projects somewhat above the same. In the bottom of the mortise are formed a number of pads 4, upon which the 80 block 3 rests. At the sides and ends of the mortises, are formed a number of locating ribs 5, which contact with the lower edge of the sides and ends of the block 3, for the purpose of automatically centering 85 the block within the mortise, thus insuring an equal space all around the block, between its faces and the inside wall of the mortise. This space is filled, after the block 3 is in position, with any suitable plastic material, 90 which is preferably an asphaltum pitch 6, shown especially in Fig. 7, which pitch is poured in, in a molten state. A suitable mouth, as 7, may be formed at any convenient point in the wall of the mortise, for the 95 introduction of said plastic material. The upper edge of the mortise projects inwardly all around, to form a stop 8 for the plastic material, so that, if it should become cracked in cold weather, or in any other 100 way, become loosened, it cannot get out of the mortise. When pitch is used and is poured into the mortise in a molten state, it adheres very tenaciously to the surface of the block, and serves, to a very large extent,—if not wholly—to hold said block in 105 position against accidental displacement, and, in fact, this holding power will, in nearly all cases, be sufficient to hold the block in position, but any other suitable 110 means may be employed and the special tie-plate 9 here shown, is arranged to perform

this office, in addition to its regular function. Said tie plate 9 is applied to the tie in the following manner:—At either side of the mortise, is formed a hooked lug 10 and an additional hooked lug 11 is formed at the outer end of said mortise. Plate 9, at the inner end thereof, or toward the center of the tie, is provided with two lugs 12, 12, adapted to be engaged by hooks 10, and at the opposite end said plate is of a substantially bifurcate conformation, the two points 13 of which are arranged to be positioned upon either side of the hook 11 which occupies notch 14. When the plate is to be applied to the tie, it is placed upon the block 3 in approximately the position which it is to occupy; it is then moved longitudinally or outward until the lugs 12 pass under the hooks of the lugs 10 and the outer edge, in proximity to the notch 14, passes beneath the hooked lug 11. The rail 15 is then placed in position and the spikes 16 are driven in, and, when so secured, the rail cannot be moved laterally so as to produce a spread track, in as much as the lugs 10 and 11 will not permit a longitudinal or outward movement of plate 9. Said plate is provided with a shoulder 17, against which the outside, lateral edge of the rail-flange 30 abuts, for the purpose of relieving the outer spikes of a portion of the strain due to the tendency of the rails to spread. The edges of the plate adjacent to the lugs 12, bear against the lugs 10 and the notch 14 engages the lug 11, and this arrangement prevents the plate from being moved by the expansion and contraction of the rail or the creeping thereof. Because of this provision, there is no necessity for using a plate 40 with flanges or claws upon its under side, which cause a detrimental mutilation of the tie. The spike-holes 16' may be located as circumstances require.

The intermediate portion of the tie, between the mortise boxes, may be of any suitable cross-section, but that here shown is T-shape, with the flanges downward, this being best adapted for the reception of ballast, as it will present a better retaining 50 surface to the ballast than any other shape, and the ballast may be easily tamped around and beneath it.

At the center of the tie, a hole 18 is formed, for convenience in handling the tie. The end webs 19 also have metal removed at 60 for the same purpose.

At the center of the tie, a lug 21 is formed, to project above the surface of the ballast of the track, to enable track-walkers and 65 pair men to readily and quickly locate the tie, this being desirable for the reason that the central portion of the tie is of such shape that it will usually be covered by the ballast of the track.

While we have here shown a tie plate in

combination with our improved tie, we do not wish to be understood as confining ourselves to its use at all times, because upon some roads where traffic is not heavy, and upon straight track, it could be safely dispensed with. 70

We claim—

1. A composite tie for railways, consisting of a metallic body having mortises for the reception of rail supports, composed of 75 blocks of wood of smaller horizontal dimensions than said mortise, means within said mortise causing the concentric positioning of said block therein, and a plastic material filling the space around said blocks.

2. A composite tie for railways, consisting of the combination of a metallic body having a mortise in each end thereof, arranged for the reception of a rail-support, a block of wood of smaller horizontal dimensions than said mortises, positioned in each of said mortises, a suitable material filling the intervening space between the surface of said block and the walls of said mortise, a lug upon either side of each of 85 said mortises, formed integrally with said body and adapted for the engagement of the lateral edges of a tie-plate, a lug at the outer end of each of said mortises, also formed integral with said body and adapted for the engagement of the outer end of a tie-plate, a tie-plate resting upon each of 90 said rail-supports, engaged by said lugs adjacent thereto, a rail resting upon said plate, and spikes securing said body, rail-support, 95 tie-plate and rail together.

3. A composite tie for railways consisting of the combination of a metallic body having a mortise in each end thereof arranged for the reception of a rail-support, 105 engaging means upon said body adjacent to said mortises, arranged to engage a tie-plate, a block of wood of smaller horizontal dimensions than said mortises positioned in each of said mortises, a suitable material filling the intervening space between the surface of each of said blocks and the walls of its respective mortise, a tie-plate adapted to 110 rest upon each of said supports and to be engaged by said engaging means, a rail resting upon each of said plates, and means securing said body, blocks, plates and rails together. 115

4. A composite tie for railways, comprising, in combination, a metallic body having mortises in either end thereof arranged for the reception of a rail-support, tie-plate-engaging means formed integrally with said body and positioned adjacent to said mortises, a block of wood of smaller horizontal dimensions than said mortises positioned in each thereof, a suitable material filling the intervening space between the surfaces of said blocks and the wall of their respective mortises, a tie-plate adapted to rest upon 120 125 130

- each of said supports and to be engaged by said engaging means, a rail resting upon each of said plates, and spikes securing said body, blocks, tie-plate and rails together.
5. A composite tie for railways comprising in combination, a metallic body provided with a mortise adjacent to either end thereof and arranged for the reception of a rail-support, tie-plate engaging-lugs formed integrally with said body and positioned adjacent to said mortises, a rail-support of smaller horizontal dimensions than said mortises and positioned in each thereof, a tie-plate positioned upon said support and arranged in engagement with the lugs of its 15 respective mortise, and means coöperating with said plate arranged to secure said body, blocks, plates and rails together.
- In testimony whereof we affix our signatures in presence of two witnesses.
